United States Patent

Des. 241,214
Patented Aug. 31, 1976

241,214

TABLE

Robert J. Szucs, Midlothian, Ill., assignor to Borg-Warner Corporation, Chicago, Ill.

Filed Aug. 5, 1974, Ser. No. 494,801

Term of patent 14 years

Int. Cl. D6—03

U.S. Cl. D6—179

FIG. 1

FIG. 2

FIG. 3

FIG. 4

FIG. 5

FIG. 1 is a perspective view of a table illustrating my new design;

FIG. 2 is a side elevational view showing the left side of the table;

FIG. 3 is a side elevational view illustrating the right side of the table;

FIG. 4 is a front elevational view of the table; and

FIG. 5 is a rear elevational view of the table.

I claim:

The ornamental design for a table, substantially as shown and described.
